UNITED STATES PATENT OFFICE

CHARLES A. JACKSON, OF RIDGEWOOD, NEW JERSEY

EMERGENCY LIGHTING SET

Application filed December 2, 1926. Serial No. 152,186.

This invention relates generally to electrical power generating equipment, and more particularly to a hydro-electric unit adapted for emergency purposes when another or 5 main source of electric current supply fails.

An object of my invention is to provide a simple, compact and very dependable unit. A further object is to provide improved means for controlling operation of the unit 10 automatically in accordance with the main supply, and more particularly to open the inlet valve automatically when the main supply fails, and to permit closing of said valve when the main supply is normal.

15 A further object is to provide an improved arrangement whereby a set of emergency lamps may be supplied with current from the main source, and to permit the emergency unit to also supply said emergency 20 lamps, even though the controlling switch therefor is open.

A further object is to provide, in my improved arrangement, a generator adapted to effect a substantially constant voltage, irrespective of load fluctuations or speed 25 variations of, the prime mover, which, in the specific aspect of the invention, is shown as a hydraulic impulse wheel, although it will, of course, be understood that any suitable or usual other type of hydraulic prime 30 mover could be used, such as a reaction turbine.

Further objects and advantages will appear from the description of the accompanying drawings, in which:—

35 Fig. 1 is an end elevation of the unit;

Fig. 2 is a front elevation of the unit taken on line 2—2 of Fig. 1;

Fig. 3 is an enlarged sectional view showing the controlling means in detail and the turbine diagrammatically;

Fig. 4 is a wiring diagram of the generator field;

Fig. 5 is a wiring diagram of the switch control for the main emergency supplies;

Fig. 6 is a diagrammatic view of a modification of the generating unit showing means for closing the turbine valve automatically when the main current supply is restored.

50 In hospitals, theaters, moving picture

houses and the like, it is highly essential that the electric current supply be continuous at all times, for should the current supply fail, the exit lights in the theaters or other necessary lights in the hospitals would go out, 55 thereby leaving the same in darkness, with the attendant dangers. In such situations, it is desirable to have an emergency source of current supply derived from a source entirely independent from the normal or main supply. To accomplish this, I use preferably a hydraulically operated generator receiving the actuating fluid therefor from the city water supply system, and there is also provided an automatic control for the 60 valve or gate mechanism controlling fluid flow to the turbine, this automatic means functioning in accordance with failure of the main source of electric current.

The turbine 1, being of the impulse type, 70 has a nozzle 2 provided with the usual needle 3 for controlling fluid flow from a supply pipe 4, which may be connected to the city water supply system or to any other suitable source. The type of flow control mechanism would, of course, vary in accordance with the style of turbine, but in general the operation would be the same for any type of turbine employed. The needle 3 extends 75 rearwardly through a bearing 5 and suitable packing associated therewith. A spring 6 is interposed between the frame 7 and a collar 8 formed on the needle stem 3', while a hand-lever 9 is pivotally connected at its lower end through suitable linkage 10 to the frame 7, and to the collar 8 as at 11. Normally, the spring 6 will tend to force the hand-lever 9 and the needle 3 in a right hand direction to permit flow to the turbine, and to control this movement so that 80 it will occur automatically when the main supply fails, there is provided a controlling mechanism comprising a latch-bar 12 pivotally connected to the hand-lever as at 13 and extending through an enlarged opening 85 14 formed in an upwardly extending portion of the frame 7. The free end of the bar 12 has a slot 15 cooperating with a guide-pin 16 fixed in the frame 7. A collar 17 90 is fixed to the bar 12, and adapted to limit 95 100

outward movement of the hand-lever 9 by engagement with an abutment 18. This abutment is supported on a pair of studs 19 fixed in the frame 7 on opposite sides of the bar 12, while nuts 20 engage opposite sides of the abutment 18 and hold the same in fixed position, this arrangement permitting the abutment 18 to be adjusted relatively to the controlling mechanism by moving the nuts 20 to any desired position along their respective studs.

A spring 21 normally tends to press the bar 12 upwardly, so that when said bar is in the position as shown in Fig. 3, a keeper-like member 22 provided with a hardened face 23 will engage a hardened member 24 fixed to the bar 12, and prevent outward movement of said bar, the tendency of which is brought about by opening spring 6.

When the free end of bar 12 is moved downwardly against the tension of spring 21, latch 23, 24 will be disengaged, and, due to the spring 6, the needle 3 will be opened to permit operation of the turbine. To effect this operation, in accordance with the failure of the main current supply, there is provided a solenoid S having a movable core C, surrounding the lower end of which is a spring interposed between the collar C¹ and the stationary part of the solenoid. The solenoid is connected to the main supply lines, so that when current is flowing therethrough, said solenoid will be energized and the core C drawn upwardly against the tension of its spring, which position is shown in Fig. 3. When the main supply fails, the solenoid core, due to its own weight and the spring cooperating therewith, will fall and strike the free end of bar 12 to free the latch 23, 24. The spring 6 will thereupon immediately move the needle valve 3 to its open position, thereby automatically starting the turbine generator unit to supply current to either the normal or emergency lighting system.

A double pole switch 25 mounted upon a suitable bracket 26, carried by the frame 7, has its movable knife portion 27 operatively connected to the bar 12 as by a stem 28, and a pin 29 swiveled in bar 12, the stem being slidably mounted in the pin of the swivel joint. As shown in Fig. 5, this switch has main terminals 30 and 31, to which is connected the main supply lines 32 and 33. A pair of central terminals 34 and 35 are connected to the normal lighting system, including wires 36 and 37, and it is to these central terminals that the switch 27 is pivotally connected, whereby the main terminals 30 and 31 may be connected to the wires 36 and 37 when the switch is in the position shown in Fig. 3. An emergency set of terminals 38 and 39 are connected to the generator G, thereby permitting current to flow from the generator through terminals 38 and 39, switch 27, and central terminals 34 and 35 to the normal

lighting lines 36 and 37, when the switch bar 12 and needle 3 are in their outward or emergency operating position. A set of emergency lamps 40 are adapted to be supplied either from the main source, as by wires 41 and 42, or by the generator G, due to the wire 43. An emergency switch 44 is placed in the wire 42. Hence it is possible, by closing the switch 44, to energize emergency lights 40 from the main supply lines 32 and 33, and to also energize said emergency lamps by the generator G, even though the switch 44 is open. In this case current flows from the generator through wire 43, the lamps 40, wire 41, terminal 34, switch 27, terminal 39, and back to the generator.

Upon restoration of the main current supply, the operator may then close down the turbine by moving the hand-lever 9 in a left-hand direction to the position shown in Fig. 3, and the latch 23, 24 will become operative due to the solenoid S being held in its upward position, spring 21 normally pressing the bar 12 to its latching position.

In order that the unit may be as simple as possible, the generator is preferably of the type shown in my co-pending application, Serial No. 135,756, filed September 16, 1926, wherein a relatively constant voltage may be maintained during varying load or speed fluctuations of the unit, this being accomplished by utilizing series fields receiving current as by wires 46 and 47 from the brushes B, while a shunt field receives its current as by wires 48 and 49, the current through wire 49 being conducted from the brushes through wire 47. The proportion between the shunt and series fields is such that a substantially constant voltage will be maintained, as described in my said co-pending application.

The modification shown in Fig. 6 discloses means whereby power flow to the turbine may automatically be shut off when the main supply current is restored. There is also shown means for exerting a fluid pressure opening force on the needle valve, which force may either supplement the opening spring 6, or, if the parts were suitably proportioned, it could be substituted for the spring. Thus, in this modification, there is provided fluid pressure means for opening and closing the fluid control valve automatically in accordance with the failure or restoration of the main current supply. The mechanism, with the exception of the features above mentioned, is identical to the preferred form, so that the same will not be described in detail. The fluid pressure opening force is effected by enlarging the needle stem 50 so as to create a differential pressure area upon which fluid in the passageway 4 will act to exert the opening force, it being noted that this force would be present at all times, even though the turbine is not running. The means for closing

the needle 3 automatically comprises a piston and cylinder arrangement 51 operatively connected through suitable linkages to the hand-lever 9. This motor could be operated by either water, air pressure, or the like, and fluid-flow to which is controlled by a suitable balanced valve 52 having inlet and exhaust pipes 53 and 54 respectively. As pressure must be exerted on the piston in only a left-hand direction, the left end of the cylinder 51 may be open, and in order to permit rapid exhaust of fluid from the closed cylinder end, a relatively large pipe 55 can be used. This will permit rapid exhaust of the fluid and relatively quick movement of the switch 27 when the movable member of valve 52 is in its lower position. When said valve is in its upper position, fluid is supplied to the cylinder through pipes 53 and 55. The movement of the balanced valve is effected by connection to the solenoid core C, and comprises a rod 56.

In operation, when the main current supply goes off, the solenoid core drops, carrying with it valve 52, whereby fluid from cylinder 51 is exhausted. The fluid pressure in passage 4, plus the tension of spring 6, then causes the needle valve 3 to open and start up the emergency unit. When the main supply of current is restored, fluid will be supplied to the cylinder 51 and move handle 9 and the nozzle needle in a left hand direction to shut down the emergency unit.

It is thus seen that in either modification the power for moving the flow control or gate mechanism is self-contained with respect to the installation in that the power is obtained either from the mechanical construction, such as the spring 6 or equivalent, or from the hydraulic arrangement whereby the actuating fluid is or may be, derived from the same source as that for driving the turbine. Therefore in one aspect of the invention there is no need for an external source of power such as a storage battery which involves not only complications but also renders the unit more or less unreliable.

While I have shown two forms which my invention may assume, it will of course be understood that various modifications may be made without departing from the spirit of my invention as set forth in the appended claims.

I claim:

1. In an electrical system the combination with a main source of electricity, of an emergency unit comprising an electrical generator and a hydraulic turbine for driving the same, flow-control mechanism for said turbine, means whereby after the flow mechanism is closed it is normally prevented from opening during maintenance of the main current supply thereby causing the unit to be inoperative, and means for releasing said latter means to effect opening of said flow mecha-

nism to start said unit, said releasing means including a solenoid controlled by current from said main source whereby upon failure of the main current supply the emergency unit starts.

2. In an electrical system, the combination with a main source of supply of electricity, of an emergency electrical generating unit having a generator, a hydraulic turbine for driving the same, flow-control mechanism for said turbine, latch mechanism adapted to prevent opening of the flow mechanism after closure thereof, and means for releasing said latch mechanism upon failure of the main source of supply, whereby the flow mechanism is adapted to be opened to start the unit.

3. In an electrical system, the combination with a main source of supply of electricity, of an emergency electrical generating unit having a generator, a hydraulic turbine for driving the same, flow control mechanism for said turbine, self-contained power means for opening said flow mechanism, and means, including a solenoid controlled by the main source of current supply, for initiating operation of said power means in order to open said flow mechanism thereby starting the unit upon failure of the main source of current, said solenoid being independent of said power means after said initiating operation is effected.

4. In an electrical system, the combination with a main source of supply of electricity, of an emergency electrical generating unit having a generator, a hydraulic turbine for driving the same, flow control mechanism for said turbine, means whereby said flow mechanism is adapted to be moved to and held in closed position so that normally the unit is inoperative, means for moving said flow mechanism to open position by power, and means responsive to failure of the main source of current for initiating operation of said power means thereby to open said flow mechanism and start the unit.

5. In an electrical system, the combination with a main source of supply of electricity, of an emergency electrical generating unit having a generator, a hydraulic turbine for driving the same, and means for controlling the operation of said turbine automatically in accordance with the supply of current from the main source, said means including turbine flow control mechanism, means for moving said flow mechanism to and normally holding it in closed position to render the unit inoperative, hydraulic means for moving said flow mechanism to open position, and means for initiating operation of said hydraulic means to open said flow mechanism and start the unit.

6. In an electrical system, the combination with a main source of supply of electricity, of an emergency electrical generating unit having a generator, a hydraulic turbine for driv-

ing the same, flow control mechanism for said turbine, means for moving said flow mechanism to only full open position when its operation is initiated, latch mechanism for preventing opening of said flow mechanism when in its closed position, and means for releasing said latch mechanism to initiate said operation automatically when the main current supply completely fails thereby starting the unit.

7. In an electrical system, the combination with a main source of supply, of an emergency electrical generating unit having a generator, a hydraulic turbine for driving the same, and means for controlling the operation of said turbine automatically in accordance with the supply of current from the main source, said means including means for creating a force constantly operative to start up operation of said turbine and having a fluid-pressure controlled element.

8. In an electrical system, the combination with a main source of supply of electricity, of an emergency lighting unit having a generator, a hydraulic turbine of the impulse type for driving the same, a nozzle having a needle for controlling fluid-flow to said turbine, means for preventing opening of said needle, and means for effecting opening movement of said needle including a solenoid energized from the main supply, said preventing means being controlled by said solenoid whereby when the main supply fails said needle will open to start the unit.

9. In an electrical system the combination with a main source of supply of electricity, of an emergency lighting unit having a generator, a hydraulic turbine of the impulse type for driving the same, a nozzle having a needle for controlling fluid-flow to said turbine, and means for controlling opening of said nozzle automatically in accordance with failure of the main supply of electricity, said means including a solenoid energized from the main supply, means whereby a constant opening force is exerted on said needle, and means associated with said needle and adapted to be controlled by said solenoid for restraining said opening force until said main source of current fails.

10. In an electrical system, the combination with a main source of supply of electricity, of an emergency lighting unit having a generator, a hydraulic turbine of the impulse type for driving the same, a nozzle having a needle for controlling fluid-flow to said turbine, means operative to produce a continuous opening force for said needle, means for restraining said opening movement, a solenoid controlled by the main supply and adapted upon failure thereof to automatically release said restraining action whereby the needle is opened by said continuous force to start the unit, and means for closing said needle and resetting said re-

straining mechanism after the electrical supply of said main source is restored.

11. In an electrical system, the combination with a main source of electricity, of an emergency lighting unit having a generator, a hydraulic impulse turbine for driving the same, a nozzle provided with a needle for controlling fluid-flow to said turbine, means for creating an opening force on said needle, a hand operated member adapted to be moved against said force to move said needle to its closed position, a latch for holding said hand operated member and needle in closed position, and a solenoid for tripping said latch to permit opening of said needle.

12. In an electrical system, the combination with a main source of electricity, of an emergency lighting unit having a generator, a hydraulic impulse turbine for driving the same, a nozzle provided with a needle for controlling fluid-flow to said turbine, means for creating an opening force on said needle, a hand-lever adapted to be moved against said force to move said needle to its closed position, a latch including a movable element for holding said hand lever and needle in closed position, a solenoid for tripping said latch to permit opening of said needle, and a switch operatively connected to said movable element.

13. In an electrical system the combination with a main source of supply of electricity of an emergency lighting unit having a generator, a hydraulic prime mover for driving the same, and means for controlling fluid-flow thereto automatically in accordance with the supply of current from the main source, said means including a flow-control element, fluid operated means creating an opening force for said element, and means whereby said force is adapted to be rendered effective to open said flow control automatically when the main source of current fails.

14. In an electrical system, the combination with a main source of supply of electricity, of an emergency lighting unit having a generator, a hydraulic prime mover for driving the same, and means for controlling fluid-flow thereto automatically in accordance with the supply of current from the main source, said means including a flow-control element, fluid-operated means for creating an opening force for said element, means whereby said force is adapted to open said control element automatically when the main source of current fails, and fluid pressure means adapted to automatically close said flow-control element when the main source of current is restored.

15. In an electrical system, the combination with a main source of supply of electricity, of an emergency lighting unit comprising a generator, a fluid operated prime mover for driving the same, flow control mechanism for said prime mover, means for automatically

- effecting opening of said flow mechanism when the main source fails including electrically controlled releasable means for controlling the starting of said turbine, means for automatically rendering said unit inoperative when said main source is restored, and self-contained power means for moving said flow control mechanism to open position when said automatic opening operation is effected.
16. In an electrical system, the combination with a main source of supply of electricity, of an emergency lighting unit comprising a generator, a hydraulic prime mover for driving the same, means for automatically effecting operation of said emergency unit when the main source instantly and completely fails, and means for automatically rendering said unit inoperative when said main source is restored, one of said means including a fluid-pressure-operated element and a solenoid operated member for controlling fluid actuation thereof, said solenoid being controlled by the main current supply.
17. In an electrical system the combination with a main source of supply of electricity, of an emergency lighting unit comprising a generator, a hydraulic prime mover for driving the same, means for automatically effecting operation of said emergency unit when the main source fails, and means for automatically rendering said unit inoperative when said main source is restored, both of said means including fluid-pressure-operated means.
18. In an electrical system, the combination with a main source of supply of electricity, of an emergency lighting unit comprising a generator, a hydraulic prime mover for driving the same, means for automatically effecting operation of said emergency unit when the main source fails, and means for automatically rendering said unit inoperative when said main source is restored, both of said means including fluid-pressure-operated means and a solenoid for controlling the fluid-operating pressure to at least one of said pressure operated means, said solenoid being connected to the main source of current.
19. In an electrical system, the combination with a main source of current supply, of an emergency lighting unit comprising a generator, a hydraulic turbine for driving the same, a nozzle for said turbine, operating means for said nozzle, and a solenoid adapted, upon failure of said main source, only to initiate functioning of said operating means thereby to open said nozzle.
20. In an electrical system, the combination with a main source of current supply, of an emergency lighting unit comprising a generator, a hydraulic turbine for driving the same, a nozzle for said turbine, operating means for said nozzle, and solenoid controlled means adapted, upon failure of said main source, to initiate functioning of said operating means thereby to open said nozzle, said solenoid controlled means having provision whereby said solenoid is adapted to remain stationary after its initiating operation and while said nozzle continues to move to its open position.
21. In an electrical system, the combination with a main source of current supply, of an emergency lighting unit comprising a generator, a hydraulic turbine for driving the same, a nozzle provided with a needle for controlling fluid flow to said turbine, a latch mechanism for holding said needle in its closed position, and means whereby upon release of said latch mechanism, said needle is moved to its open position.
22. In an electrical system, the combination with a main source of current supply, of an emergency lighting unit adapted for cooperation with said main source of supply of electricity, said unit comprising a generator, a hydraulic impulse turbine for driving the same, a nozzle provided with a needle for controlling fluid flow to said turbine, a spring disposed so as to move said needle in an opening direction, and latch mechanism for restraining the action of said spring so as to hold the needle in its closed position and adapted upon release to permit said spring to move said needle to its open position.
23. An emergency lighting unit comprising in combination, a generator, a hydraulic turbine, mechanism for controlling flow to the turbine, means for exerting a force on said mechanism to tend constantly to move the same to an open position, and a latch mechanism adapted to hold said flow control mechanism in its closed position and to be released to permit opening thereof.
24. An emergency lighting unit comprising a generator, a hydraulic impulse turbine for driving the same, a nozzle provided with a needle for controlling fluid flow to said turbine, means for holding said needle in its closed position including a latch having a latch bar which extends for a substantial distance substantially parallel to said needle, means creating a force constantly exerted on said needle in an opening direction, and a solenoid adapted to move one end of said latch bar to release said latch whereby said needle will move to its open position.
25. An emergency lighting unit comprising a generator, a hydraulic turbine for driving the same, a flow control mechanism provided with means which constantly exerts a force on said flow mechanism in an opening direction, releasable mechanism for holding said flow control mechanism in a closed position, and means for releasing said releasable mechanism by imparting a striking blow thereto including a solenoid for effecting said blow.

23. An emergency lighting unit comprising a generator, a hydraulic impulse turbine for driving the same, a nozzle casing provided with a needle rod for controlling fluid flow to said turbine, said needle rod extending outwardly from said nozzle casing, a lever connected to the outer end of said needle rod and extending substantially in an upward direction, means for holding said needle and lever in a closed position, and means for releasing the same including a supporting structure carried above and by said nozzle housing, operating members connected to said lever and extending inwardly to said supporting structure, and means carried within said structure for operating upon said inwardly extending members.

27. An emergency lighting unit adapted for cooperation with a main source of supply of electricity, said unit comprising a generator, a hydraulic impulse turbine for driving the same, a nozzle housing provided with a needle rod for controlling fluid flow to said turbine, said needle rod having its outer end extending outwardly from said nozzle housing, means constantly exerting a force for said needle in an opening direction, a hand lever connected to the outer end of said needle, a supporting structure carried by and disposed above said nozzle housing, a solenoid and switch mechanism disposed within said supporting structure, and means connected to said hand lever and extending inwardly to said structure and having operative connection with said switch and solenoid mechanisms whereby, upon failure of said main source of supply of electricity, said solenoid functions to effect opening of said needle with consequent throwing of said switch.

28. An emergency lighting unit comprising a generator, a hydraulic turbine for driving the same, flow control mechanism for said turbine, and means for controlling said flow mechanism including latch mechanism adapted to be held in latched position when said flow control mechanism is closed, means for releasing said latch mechanism, and self-contained power means for moving said flow mechanism to open position when said latch mechanism is released.

29. An emergency lighting unit comprising, a generator, a hydraulic turbine for driving the same, a flow control mechanism for said turbine, and means for controlling said flow control mechanism including releasable mechanism adapted when released to permit opening of said flow control mechanism, and solenoid controlled means for releasing said releasable mechanism by imparting a striking blow thereto.

30. In an electrical system, the combination with a main source of supply of electricity, of an emergency electrical generating unit having a generator, a hydraulic

turbine for driving the same, flow control mechanism for said turbine, a switch, means for actuating said switch upon movement of said flow control mechanism, latch mechanism adapted to prevent opening of the flow mechanism after closure thereof, and means for releasing said latch mechanism upon failure of the main source of supply whereby said flow mechanism is adapted to be opened to start the unit.

31. In an electrical system, the combination with a main source of supply of electricity, of an emergency electrical generating unit having a generator, a hydraulic turbine for driving the same, flow-control mechanism for said turbine, a switch positively connected to said flow control mechanism whereby said switch is actuated directly upon movement of said flow control mechanism, latch mechanism adapted to prevent opening of the flow mechanism after closure thereof, and means for releasing said latch mechanism upon failure of the main source of supply, whereby the flow mechanism is adapted to be opened to start the unit and throw said switch.

32. In an electrical system, the combination with a main source of supply of electricity, of an emergency electrical generating unit having a generator, a hydraulic turbine for driving the same, flow control mechanism for said turbine, means whereby said flow mechanism is adapted to be moved to and held in closed position so that normally the unit is inoperative, means for moving said flow mechanism to open position by power, switch mechanism, means for throwing the same when said flow mechanism is moved to its open position, and means responsive to failure of the main source of current for initiating operation of said power means thereby to open said flow mechanism and start the unit and to throw said switch.

33. In an electrical system, the combination with a main source of supply of electricity, of an emergency electrical generating unit having a generator, a hydraulic turbine for driving the same, flow control mechanism for said turbine, means whereby said flow mechanism is adapted to be moved to and held in closed position so that normally the unit is inoperative, means for moving said flow mechanism to open position by power, a switch, means for effecting a positive mechanical connection between said power means and switch thereby to actuate said switch upon opening of said flow mechanism, and means responsive to failure of the main source of current for initiating operation of said power means thereby to open said flow mechanism and start the unit and to throw said switch.

CHARLES A. JACKSON.
